DESIGN FOR A MASSAGE MITT

Nellie L. Reid, Ferndale, Mich.

Application October 24, 1940, Serial No. 96,062

Term of patent 7 years

To all whom it may concern:

Be it known that I, Nellie L. Reid, a citizen of the United States, residing in Ferndale, in the county of Oakland, State of Michigan, have invented a new, original, and ornamental Design for a Massage Mitt, of which the following is a specification, reference being had to the accompanying drawing, forming a part thereof, wherein:

Fig. 1 is a view in perspective of a massage mitt showing my new design.

Fig. 2 is a view in outer end elevation of the same.

Fig. 3 is a view in rear elevation of the same.

Fig. 4 is a longitudinal sectional view taken along the line 4—4 of Fig. 1, looking in the direction indicated by the arrows.

I claim:

The ornamental design for a massage mitt, as shown.

NELLIE L. REID.
